United States Patent Office

Des. 222,941
Patented Feb. 8, 1972

222,941

DEPTH METER

Robert C. Knutson, Rosemount, Minn., assignor to
Vexilar, Inc., Minneapolis, Minn.

Filed Sept. 11, 1970, Ser. No. 24,948

Term of patent 14 years

Int. Cl. D10—04

U.S. Cl. D26—1

FIG. 1

FIG. 2

FIG. 3

FIG. 4

FIG. 5

FIG. 5

FIG. 6

FIG. 1 is a front perspective view of the depth meter showing my new design; and

FIG. 2 is a top plan view thereof;

FIG. 3 is a rear elevational view thereof;

FIG. 4 is a left side elevational view, the right side being a mirror image thereof; and

FIG. 5 is a front elevational view thereof;

FIG. 6 is a front perspective view of a modified form of FIG. 1, wherein dual, circular knobs have been substituted for the rectangular switch button; and

FIG. 7 is a front perspective view of another modified form of FIG. 1, wherein a knob has been substituted for the rectangular switch button.

I claim:

The ornamental design for a depth meter, as shown.
